UNITED STATES PATENT OFFICE.

JOHN W. OVERTURF, OF BILLINGS, MONTANA.

DESIGN FOR A COMBINED PIPE CLEANER AND TAMP AND MATCH-STRIKER.

51,422.

Specification for Design.

Patented Oct. 23, 1917.

Application filed September 6, 1917. Serial No. 190,089. Term of patent 3½ years.

To all whom it may concern:

Be it known that I, JOHN W. OVERTURF, a citizen of the United States, residing at Billings, in the county of Yellowstone and State of Montana, have invented a new, original, and ornamental Design for a Combined Pipe Cleaner and Tamp and Match-Striker, of which the following is a specification, reference being had to the accompanying drawing, forming part thereof.

Figure 1 is a perspective view, and

Fig. 2 is a perspective view looking in the opposite direction to Fig. 1.

I claim:—

The ornamental design for a combined pipe cleaner and tamp and match striker, as shown.

JOHN W. OVERTURF.
